DESIGN FOR A TEXTILE FABRIC OR SIMILAR ARTICLE OF MANUFACTURE

Paul Reiman, New York, N. Y., assignor to Tioga Silk Company, Inc., New York, N. Y., a corporation of Pennsylvania

Application January 24, 1934, Serial No. 50,497

Term of patent 3½ years

To all whom it may concern:

Be it known that I, PAUL REIMAN, a citizen of Germany, residing at New York city, county of New York, State of New York, have invented a new, original, and ornamental Design for a Textile Fabric or Similar Article of Manufacture, of which the following is a specification, reference being had to the accompanying drawing, forming a part thereof, and showing a face view of a piece of textile fabric embodying my design, the shading being used to indicate difference in colors and not to designate specific colors.

The design is intended to be repeated on the fabric as shown.

I claim:

The ornamental design for a textile fabric or similar article of manufacture substantially as shown and described.

PAUL REIMAN.
